(57) **CLAIM**

The ornamental design for a gutter guard, as shown and described.

DESCRIPTION

FIG. 1 is a perspective view of a gutter guard;

FIG. 2 is another perspective view thereof;

FIG. 3 is a top plan view thereof;

FIG. 4 is a bottom plan view thereof;

FIG. 5 is a front elevation view thereof;

FIG. 6 is an enlarged detailed view of portion 6 of FIG. 5;

FIG. 7 is a rear elevation view of FIG. 1;

FIG. 8 is an enlarged detailed view of portion 8 of FIG. 7;

FIG. 9 is a right-side elevation view of FIG. 1;

FIG. 10 is an enlarged detailed view of portion 10 of FIG. 9;

FIG. 11 is a left-side elevation view of FIG. 1; and,

FIG. 12 is an enlarged detailed view of portion 12 in FIG. 11.

The evenly spaced broken lines indicate cutoff boundaries for enlarged detailed portion views and form no part of the claim.

1 Claim, 8 Drawing Sheets
